(57) **CLAIM**

The ornamental design for a loop hand tool grip, as shown and described.

DESCRIPTION

FIG. 1 is an isometric view of the loop hand tool grip;

FIG. 2 is a front view of the loop hand tool grip;

FIG. 3 is a back view of the loop hand tool grip;

FIG. 4 is a top view of the loop hand tool grip;

FIG. 5 is a bottom view of the loop hand tool grip;

FIG. 6 is a left side view of the loop hand tool grip; and,

FIG. 7 is a right side view of the loop hand tool grip.

The phantom lines shown in the drawings represent environmental structure and form no part of the claimed design.
